UNITED STATES PATENT OFFICE.

WLADYSLAW OJCZYK, OF CLEVELAND, OHIO.

HAT-FASTENER.

1,175,173.

Specification of Letters Patent. Patented Mar. 14, 1916.

Application filed August 30, 1915. Serial No. 47,986.

To all whom it may concern:

Be it known that I, WLADYSLAW OJCZYK, a subject of the Emperor of Austria-Hungary, residing at Cleveland, in the county 5 of Cuyahoga and State of Ohio, have invented certain new and useful Improvements in Hat-Fasteners, of which the following is a specification.

This invention relates to certain new and 10 useful improvements in hat fasteners.

An object of the present invention is to provide a fastener for ladies' hats in which the same is secured in the hat and hair of the wearer in a manner to prevent accidental 15 displacement of the same and subsequent loss.

A further object of the invention is to provide a hat fastener in the form of a pin that passes completely through the hat 20 and hair of the wearer with a protecting head positioned on the projecting end of the pin and connected to the pin head to prevent the accidental displacement of the same.

With these general objects in view and others that will appear as the nature of the invention is better understood, the same 25 consists in novel construction, combination and arrangement of parts hereinafter more 30 fully described, illustrated in the accompanying drawings, and then claimed.

In the drawings forming a part of this application and in which like designating characters refer to corresponding parts 35 throughout the several views:—Figure 1 is a perspective view of a hat upon the head of a wearer with the present form of fastening means in operative position in the head. Fig. 2 is a side elevational view, partly 40 broken away, of the improved hat fastening device, the point protecting head being partly shown in section, better to illustrate the interior pin-receiving recess. Fig. 3 is an end elevational view of the point 45 protecting head, and, Fig. 4 is a sectional view taken on line IV—IV of Fig. 3, showing the notched face on the interior of the point protecting head for gripping the point of the pin.

According to my invention there is provided a hat fastener including a pin element with a head formed integral therewith or otherwise secured thereto while a point protecting head is adapted to be mounted on 50 the point of the pin. The main pin head and the point protecting head may be con-

structed of identical shape to present a pin fastening of neat appearance, the same being preferably cone-shaped as shown, while the point protecting head is longitudinally slotted from the pin-receiving end toward the enlarged end and internally constructed in a manner to frictionally grip the pin and prevent accidental displacement thereof. An elastic cord or similar fastening means is connected at each of its ends to the fixed head and point protecting head and is adapted to be positioned exteriorly of the hat as is indicated while the pin passes therethrough and through the hair of the 70 wearer, the elastic cord further holding the point protecting head in assembled position as shown.

Referring more in detail to the accompanying drawing, the reference numeral 5 75 designates the crown of a hat through which the pin shank 6 of the hat fastener is adapted to extend. The pin shank 6 is pointed at one end to provide a hat and hair entering end while the other end thereof is provided 80 with a fixed head 7 of any suitable shape or design but preferably of cone-shape as shown.

A point protecting head 8 is adapted to be received on the pointed end of the pin 85 shank 6 after the same passes through the hat 5 and is of peculiar construction to prevent the accidental displacement thereof from the pin. This point protecting head 8 is preferably formed of the same shape 90 and design as the fixed head 7, and as shown is of cone-shape, the same being longitudinally slotted from the smaller end thereof to a point adjacent the larger end to provide a pair of resilient side member 9. The side 95 members 9 are slightly spaced as shown in Fig. 3 while the central portion of one member is provided with a longitudinal ridge or tongue 10 that co-operates with a longitudinal recess or groove 11 in the opposing side members 9. Transverse ridges and grooves 12 are formed in the tongue and groove 10 and 11 and are adapted to frictionally engage the pin point to prevent the displacement of the protecting head 8.

Each of the heads 7 and 8 is provided with an eye-bolt 13 to which is fastened the ends of an elastic cord 14. In the operative position as shown in Fig. 1, the pin shank 6 passes through the hat 5 and hair of the 110 wearer and has the point protecting head 8 received on the projecting pointed end there-

of, the pin end entering the central portion of the slot between the two members 9 and is engaged by the ridges or shoulders 12 formed on said members. The elastic cord 14 is positioned exteriorly of the hat and engages the crown thereof and tends further to hold the protecting head 8 upon the pin.

While the form of the invention herein shown and described is what is believed to be the preferred embodiment thereof, it is nevertheless to be understood that various forms, modifications and arrangements of the parts may be made without departing from the spirit and scope of the invention as claimed.

What I claim as new is:—

1. A hat fastener including a pin shank and a head formed integral therewith, a point protecting head longitudinally slotted

for a portion of its length to provide a pair 20 of opposing side members, a longitudinal tongue and groove formed on the opposed faces of the side members, transverse ridges formed on said tongue and groove, the said pin adapted to be received within said 25 tongue and groove and be frictionally engaged by said ridges, and a flexible cord connected at its ends to the fixed head and the protecting head.

2. A point protector for hat pins comprising a resilient head having a slot extending from side to side thereof substantially throughout its length and provided on one face with an upstanding corrugated rib and on the remaining face with a groove having 35 a corrugated bottom.

In testimony whereof I affix my signature.

WLADYSLAW OJCZYK.
